CLAIM

We claim the ornamental design for a camera mount, as shown and described.

DESCRIPTION

FIG. 1 is a front perspective view of a camera mount of the present disclosure;

FIG. 2 is a front elevational view of the camera mount of FIG. 1;

FIG. 3 is a rear elevational view of the camera mount of FIG. 1;

FIG. 4 is a left side elevational view of the camera mount of FIG. 1;

FIG. 5 is a right side elevational view of the camera mount of FIG. 1;

FIG. 6 is a top plan view of the camera mount of FIG. 1; and, FIG. 7 is a bottom plan view of the camera mount of FIG. 1.

Broken lines are environmental only and form no part of the claimed design.

1 Claim, 4 Drawing Sheets
